UNITED STATES PATENT OFFICE.

JESSE EDWARD ABRAMS, OF CANONSBURG, PENNSYLVANIA, AND IVAR FREDOLF WARME, OF SYRACUSE, NEW YORK, ASSIGNEES, BY MESNE ASSIGNMENTS, TO CONTINENTAL CAN COMPANY, INC., A CORPORATION OF NEW YORK.

CAN-CLOSING MACHINE.

1,103,643.

Specification of Letters Patent.

Patented July 14, 1914.

Application filed April 28, 1911. Serial No. 623,513.

To all whom it may concern:

Be it known that we, JESSE E. ABRAMS and IVAR F. WARME, citizens of the United States, residing at Canonsburg, in the county of Washington, State of Pennsylvania, and Syracuse, Onondaga county, New York, respectively, have invented certain new and useful Improvements in Can-Closing Machines, of which the following is a description, reference being had to the accompanying drawing, and to the letters and figures of reference marked thereon.

The invention relates to new and useful improvements in can closing machines, that is, machines for double-seaming an end or a cover onto a filled can.

An object of the invention is to provide means which may be manually operated for placing the covers underneath the seaming head, and between the rotary chuck and the can body.

A further object of the invention is to provide means for centering the can cover underneath the seaming head and over the can body and for centering the can body relatively to the seaming head, and round up the same for the cover.

A still further object of the invention is to provide means for placing covers under the seaming head; centering the same relative to the seaming head and supporting said cover temporarily; centering a can body underneath the cover and lowering the cover onto the can body and holding the same on the can body until secured thereto by the seaming roll.

These and other objects will in part be obvious, and will in part be hereinafter more fully described.

In the drawings which show by way of illustration one embodiment of the invention, Figure 1 is a front view of the closing machine having our improvements applied thereto; Fig. 2 is a side view thereof; Fig. 3 is a plan view of the cover feed and centering device; Fig. 4 is a sectional view through the cover feed, showing the plunger for separating the cover from the stack; Fig. 5 is a side view of the parts shown in Fig. 3; Fig. 6 is a sectional view showing a can body, a cover supported above the same and the seaming head before brought into engagement with the cover; Fig. 7 is a similar

view, showing the cover seated in the can body by the seating pad; Fig. 8 is a similar view, showing the final operation of the seaming rolls; and Fig. 9 is a similar view showing the can closed and the parts returned to normal position for discharging the cans.

In carrying out the invention, a suitable frame 1 is provided on which is mounted a main shaft 2, which may be driven in any desired way. A countershaft 3 is operated from the main shaft through a belt connection 4. The seaming head 5 is carried by a vertical shaft 6, which is mounted in bearings 7, 7, supported by the frame 1. The shaft 6 carrying the seaming head is rotated through the gear connection 8 with the countershaft 3.

The seaming head includes an inner and outer sleeve 9 and 10, see Fig. 6. Mounted on the sleeve 10 is a curling roll 11 and a flattening roll 12, for performing the usual first and second seaming operations for connecting a can end or cover to a can body by a rolled double seam. These seaming rolls are carried by levers 13, which are operated by cams on the sleeve 9, in the usual well known manner.

A chuck 14 is mounted on the sleeve 10, and the sleeve is free to rotate about said chuck. Located centrally of the chuck and seaming head is a seating pad 15, which is carried by a stem 16 extending upwardly through the shaft 6, which is hollow, and said stem at its upper end carries a collar 17, which is connected to a lever 18 operated from a cam on a cross shaft 19, which may be operated in any desired way from the countershaft 3. The shaft 6 is moved up and down in order to bring the seaming head into contact with the cover, and also in order to bring the seaming rolls into contact with the edge of the cover by a bell crank lever 20, which is operated through the arm 21 which carries a roller running in a cam groove 22 in a disk on the shaft 19.

Underneath the seaming head is a support 23, on which the filled cans to be closed or to have covers attached thereto, may rest and move. This support 23 is adjustably carried by the frame 1, and may be moved up and down by a screw 24, so as to position the support for different sized

cans. The filled cans are moved along the support by a drum 25, which is provided with a thread 26. The thread 26 extends upwardly through a groove in the support 23, and engages the lower ends of the cans to move the same on the support. Said thread is preferably so formed that when a can is brought to the seaming station it will remain at the seaming station while the seaming head is brought down onto the can to close the same, after which the can may be ejected from underneath the seaming head. This drum feed is more fully shown and described in the patent granted 15 to Krummel and Taliaferro, No. 931,434, August 17th, 1909. The drum 25 is operated by a shaft 27, which is in turn operated by the shaft 19.

The covers for closing the cans are placed 20 in a stack 28, which consists, as herein shown, of three rods 29 for holding the stack of cans, and a supporting base 30 for said rods. The stack holder is mounted on a supporting plate 31, which is connected 25 to a slide 32 mounted to move in guides 33 carried by a bracket 34, which is secured in any desired way to the frame 1 of the machine. The slide 32 is attached to a rod 35, which extends at its upper end through a 30 perforated lug 36 formed on the side of the lever arm 20 there being sufficient play to allow said lever arm to reciprocate the slide 32. A collar 37 is secured at the upper end of the rod 35. The slide 32 will, therefore, 35 move up and down with the lever 20 which moves the seaming head up and down.

The supporting plate 31 is cut away at 38 to form a ring-shaped centering device for the can body, and also a support for the can 40 cover. The lower edge of the opening in the plate 31 is tapered as at 39 (see Figs. 6 to 9), and the upper face of the plate is cut away to form a supporting ledge 40, for the cover. The covers are moved forward 45 on to the supporting ledge 40 by a pusher 41, which is mounted to reciprocate in guiding grooves formed in the supporting plate 31. The plate 31 is cut away on its upper face to form a recess 42, which is shaped 50 substantially like the under face of the cover, and this recess 42 extends from a point underneath the stack to the opening 38 forming the supporting device for the cover and centering device for the can body. 55 This recess in the upper face of the supporting plate 31 extends underneath the base 30 of the stack, so that the covers in the stack will rest on the bottom of the recess when the pusher 41 is retracted, and as the pusher 41 is moved forward, the cover may be carried along the recess underneath the support 30, and on to the supporting ledge 40.

The base 30 is so disposed relative to the recess that only one cover at a time may pass 65 underneath the support 30. The pusher 41

is preferably formed with a sharp separating lip 43 at its front upper face, which will enter between the can covers in the stack and aid in separating the lower cover from the stack, so that when the pusher is moved forward only the lower cover in the stack will be carried along the recess on to the supporting ledge 40. The pusher 41, as herein shown, is formed with a handle 44, whereby said pusher may be manually operated. 70 75

In the operation of the device, the filled can bodies 45 are spaced on the drum feed which carries one can body after another underneath the seaming head. The operator grasps the handle 44 and moving the pusher forward carries a cover 46 on to the supporting ledge 40, see Figs. 6 to 9. The plate 31 is so disposed underneath the seaming head that when the cover 46 is pushed forward as far as it can be moved by the pusher, said cover will be centered directly underneath the seaming head which is rotating continuously. The seaming head is now moved downward through the operation of the cam on the lever 20. This also carries the supporting plate 31 with the cover thereon downward toward the can body 45, until the cover rests on the can body, as shown in Fig. 7. The tapered wall 39 of the supporting plate 31 will engage the flange at the upper edge of the can body, and center the same relative to the cover and the seaming head, so that the cover will be properly seated in the can body. Not only does the tapered wall of the opening in the supporting plate serve to center the can body relative to the seaming head, but said tapered opening will also serve as a means for rounding up the can body. This is one of the essential features of the present invention. Can bodies of the sanitary type, that is, those which are merely flanged at the upper end, as they are handled often become out of true so that sometimes it is impossible to seat the can end in the can body before it is brought back to its proper rounded shape. This distorting of the open end of the can body is however within the range of the outer opening at the lower end of the tapered ring and as the ring is forced down over the can, it will be engaged by the tapered walls of the ring and gradually brought back into its normal condition for the receiving of the can end. The seating 105 pad 15, through the action of the lever 18, moves forward in advance of the seaming head, engages the cover and crowds the same into the can body, as shown in Fig. 7. A further downward movement of the seaming head brings the chuck into engagement with the cover, so that the can body is properly held for the seaming action. The supporting plate 31 will also move downward, with the downward movement of the shaft 6, 110 115 120 125 130

carrying the seaming head, so as to move the plate out of the way of the seaming rolls which are brought first one and then the other into contact with the flange on the can cover and can body to form a double seam. After the double seam is completed, the seaming head will move upward and release the can. The plate 31 will also move upward with the seaming head and the can cover which is now smaller in diameter than before it was attached to the can body, may move downward through the opening 38 in the supporting plate 31, and the seaming head and centering device will thereby be entirely released from the can body, so that it may be ejected from the machine.

It will thus be seen that by the above mechanism, the can covers are carried by mechanical means underneath the seaming head and centered relative thereto. The covers are also temporarily supported until a can body is brought underneath the cover. Furthermore, when the parts are in proper position and the seaming head descends to close the can, the can body will be centered, the cover placed thereon and seated in the can body, and then the cover secured to the can body by a double seam.

It is obvious that minor changes in the details of construction may be made without departing from the spirit of the invention as set forth in the appended claims.

Having thus described the invention what is claimed as new and desired to be secured by Letters Patent, is:—

1. The combination of a can support, a seaming head, seaming rolls carried thereby, means for rotating said seaming head, means for moving said seaming head up and down relative to said support, a can end feeding device movable with said seaming head and including a support for the can end, and a movable member for positively engaging and moving the can end on the support to a position underneath the seaming head.

2. The combination of a supporting frame, a support for can bodies carried thereby, a seaming head mounted on said supporting frame, means for rotating said seaming head, seaming rolls carried by said seaming head, a can end support extending underneath said seaming head and held in fixed relation thereto, said support having a circular opening in line with the axis of the rotating seaming head, said support having at its upper face a seat for the can end which is concentric with said opening, means for moving a can end on said can end support underneath said seaming head on to said can end seat, said opening being tapered downwardly and outwardly toward its lower face below said seat, so as to form a cone-shaped wall for rounding up and centering the open end of the can body relative to the seaming head and can end, and means for moving said seam-

ing head and can end support relative to said can body support for presenting the can body to the seaming head.

3. The combination of a supporting frame, a support for can bodies carried thereby, a seaming head mounted on said supporting frame, means for rotating said seaming head, seaming rolls carried by said seaming head, a can end support extending underneath said seaming head and held in fixed relation thereto, said support having a circular opening in line with the axis of the rotating seaming head, said support having at its upper face a seat for the can end which is concentric with said opening, means for moving a can end on said can end support underneath said seaming head on to said can end seat, said opening being tapered downwardly and outwardly toward its lower face below said seat, so as to form a cone-shaped wall for rounding up and centering the open end of the can body relative to the seaming head and can end, means for moving said seaming head and can end support relative to said can body support for presenting the can body to the seaming head, a seating pad, and means for moving said seating pad into contact with the can end on said support for holding said can end on its seat until said can end is seated in the can body.

4. The combination of a supporting frame, a support for can bodies carried thereby, a seaming head mounted on said supporting frame, means for rotating said seaming head, seaming rolls carried thereby, a can end support extending underneath said seaming head and held in fixed relation thereto, said support having a circular opening therethrough in line with the axis of the rotating seaming head, said support at the upper face thereof having a recess forming a seat for a can end with its center substantially in alignment with the center of said opening and the axis of the rotating seaming head, means for moving a can end along said can end support on to said seat, said opening being tapered downwardly and outwardly toward its lower face so as to form a cone-shaped wall for rounding up and centering the can body, and means for moving said seaming head and can end support relative to said can body support for presenting a can body to the seaming head.

5. The combination of a supporting frame, a support for can bodies carried thereby, a seaming head mounted on said supporting frame, means for rotating said seaming head, seaming rolls carried thereby, a can end support extending underneath said seaming head and held in fixed relation thereto, said support having a circular opening therethrough in line with the axis of the rotating seaming head, the diameter of said opening being slightly less than the diameter of a can end and slightly

greater than the extreme diameter of the flange at the upper end of the can body, said support at the upper face thereof having a recess forming a seat for a can end with its center substantially in alignment with the center of said opening and the axis of the rotating seaming head, means for moving a can end along said can end support on to said seat, said opening being tapered down-
 5 wardly and outwardly toward its lower face so as to form a cone-shaped wall for rounding up and centering the can body, and means for moving said seaming head and can end support relative to said can body support for preventing a can body to the seaming head.

6. The combination of a supporting frame, a support for can bodies carried thereby, a seaming head mounted on said supporting frame, means for rotating said seaming head, seaming rolls carried thereby, a can end support extending underneath said seaming head and held in fixed relation thereto, said support having a circular opening therethrough in line with the axis of the rotating seaming head, the diameter of said opening being slightly less than the diameter of a can end and slightly greater than the extreme diameter of the flange at
 20 the upper end of the can body, said support at the upper face thereof having a recess forming a seat for a can end with its center substantially in alignment with the center of said opening and the axis of the rotating
 25 seaming head, means for moving a can end along said can end support on to said seat, said opening being tapered downwardly and outwardly toward its lower face so as to form a cone-shaped wall for rounding up
 30 and centering the can body, means for moving said seaming head and can end support relative to said can body support for presenting a can body to the seaming head, a seating pad, and means for moving said seating pad into contact with the can end on said support for holding said can end on its seat until said can end is seated in the can body.

7. The combination of a seaming head, seaming rollers carried thereby, means for rotating said seaming head, means for moving said head up and down relative to a support for can bodies, and means for feeding can ends to the seaming head, including a supporting plate, a base mounted on the supporting plate, stack holder carried by the base, said supporting plate having a recess extending underneath the base, means sliding underneath the base for forcing a can end from the stack to a position underneath the seaming head.

8. The combination of a seaming head, seaming rolls carried thereby, means for rotating said seaming head, and means for moving said seaming head up and down

relative to a support for the can bodies, and means for feeding can ends to said seaming head, including a supporting plate having an opening therein with the center thereof in line with the axis of the seaming head, a ledge formed about said opening for supporting a can end, and a movable member for engaging and positively pushing a can end to a position underneath the seaming head on to said supporting ledge.

9. The combination of a seaming head, seaming rolls carried thereby, means for rotating said seaming head, means for moving said seaming head up and down relative to the support for the can body, and means for feeding can ends to the seaming head, including a supporting plate having an opening with the center thereof in line with the axis of the seaming head, a ledge formed about said opening for supporting a can end, said supporting plate having an outwardly extending part, a stack holder carried on said part, said plate having a recess extending underneath the stack holder and leading to the supporting ledge, a pusher mounted in said supporting plate for separating a can end from the stack and moving the same along said recess on to said supporting ledge.

10. The combination of a seaming head, seaming rolls carried thereby, means for rotating said seaming head, a support for can bodies, means for applying can ends to the bodies, comprising a member having tapered walls adapted to engage the can body and round up the same to receive the can end, means for moving said member relative to the can body and a reciprocating member movable underneath the seaming head for positively placing the can ends underneath said head.

11. The combination of a seaming head, seaming rolls carried thereby, means for rotating the head, a support for the can bodies, and means for applying can ends to the bodies comprising a supporting plate extending beneath the seaming head and having an opening therein, the center of which is in axial alignment with the seaming head, the inner walls of said opening being tapered, whereby the can body is rounded up and centered relative to the seaming head, and a member reciprocating underneath said head for engaging and positively placing a can end in the seat on said supporting plate.

12. The combination of a seaming head, a support for can bodies, means for moving the seaming head up and down relative to the support, a supporting plate moving up and down with the seaming head, said supporting plate having an opening therein with the center in line with the axis of the seaming head, the under surface of the opening in said plate being tapered whereby as

5 said plate moves down with the seaming head, the same will engage and center the can body underneath the seaming head, said plate having a ledge formed on its upper face around said opening for supporting a can end, and means for placing a can end on said ledge.

13. The combination of a seaming head, a support for can bodies, means for moving the seaming head up and down relative to the support, a supporting plate moving up and down with the seaming head, said supporting plate having an opening therein with the center in line with the axis of the 10 seaming head, the under surface of the opening in said plate being tapered whereby as said plate moves down with the seaming head, the same will engage the flange of the can body and round up the same and center

the can body underneath the seaming head, 20 said plate having a ledge formed on its upper face around said opening for supporting a can end, a can end stack holder carried by said plate, and a pusher for engaging a can end in said stack, separating 25 the same from the stack and placing the same on said ledge.

In testimony whereof we affix our signatures, in presence of two witnesses.
